United States Patent Office

Des. 177,811
Patented May 29, 1956

177,811

FIRE ALARM BOX OR SIMILAR ARTICLE

Willis G. Holmes, Pembroke, Mass.

Application December 7, 1955, Serial No. 39,212

Term of patent 14 years

(Cl. D72—1)

Fig. 1

Fig. 2

Fig. 3

Fig. 4

Fig. 1 is a top plan view of a fire alarm box or similar article showing my new design;

Fig. 2 is a front elevational view thereof;

Fig. 3 is a side elevational view; and

Fig. 4 is a bottom plan view.

The dominant features of my new design are shown in solid lines.

I claim:

The ornamental design for a fire alarm box or similar article, substantially as shown and described.
